CARL H. JOHNSTON, OF PORTLAND, OREGON.

MILK-BOTTLE LOCK.

1,203,200.

Specification of Letters Patent. Patented Oct. 31, 1916.

Application filed January 20, 1916. Serial No. 73,171.

To all whom it may concern:

Be it known that I, CARL H. JOHNSTON, a citizen of the United States, residing in the city of Portland, county of Multnomah and State of Oregon, have invented certain new and useful Improvements in Milk-Bottle Locks, of which the following is a specification.

My invention relates to milk bottle locks, and more particularly to a locking device adapted to receive and have locked therein a full bottle of milk, the release of which from said device requires that an empty bottle and a coin in payment for the milk; or two coins, be inserted therein; an empty bottle and a coin, being required to unlock the device for removal of the full bottle; or, a coin in payment for the milk, and a coin in payment for the bottle, being necessary to be inserted in two different coin slots before the full bottle of milk can be removed by the customer.

The main object of the invention is to provide a device in which the customer is required to pay for the bottle of milk and return an empty bottle before he can remove the bottle of milk from the device, or, if he has no empty bottle, he can insert a coin in payment for the full bottle of milk, and a coin in payment for the bottle itself, and thus secure the release of the bottle of milk. He cannot, however, secure the release of the bottle of milk otherwise.

In order that others may understand my invention I have shown a practical embodiment thereof in the accompanying sheet of drawings, which I will now describe.

Figure 1 is a front elevation of a device embodying my invention; Fig. 2 is a top plan view thereof; Fig. 3 is a horizontal sectional view on the line 3—3, of Fig. 1, showing the locking members open and with only an empty bottle indicated in broken lines in the device; Fig. 4 is a vertical sectional view taken on the line 4—4 of Fig. 1; and Fig. 5 is a similar view on the same line looking in the opposite direction.

Referring more in detail to the drawings, the invention as here shown for purposes of illustration, comprises a two compartment structure, one compartment of which is adapted to receive a full bottle of milk,

which is exposed to view, excepting as to its head, by means of which it is supported and locked in place, as at the left hand side of Fig. 1, and the other compartment of which is adapted to receive an empty bottle which is wholly inclosed within the device when it is shut, as indicated at the right hand side of Fig. 1. The main body structure, therefore, comprises a box, or casing, of T-shape in cross section, as will be clear from Fig. 3, which contains most of the locking mechanism hereinafter described.

The back of the structure, or that part corresponding to the top of a T, is designated 1, while the middle portion of the device, or that portion corresponding to the stem of a T, is designated 2. A top plate 3, is mounted upon and covers the entire top of the device, as clearly indicated in Figs. 1 and 2. Through this top plate 3, leading to the bottom portion of the middle box 2, are two coin chutes, designated 4 and 5, the chute 4 being adapted for dimes, and the chute 5 being adapted for nickels, shown clearly in Figs. 2 and 4. At the left hand side of the device, a wall member 6, extends forwardly, as indicated in Fig. 3, forming a compartment having a supporting shelf 7, therein, with a coöperating supporting member 8, hingedly connected thereto, as at 9, and provided with a corresponding supporting shelf 10, said supporting shelves 7 and 10, being adapted to clamp around the neck of a bottle of milk placed therein, in the manner indicated in Fig. 1, when said hinged supporting member 8, is closed. Said hinged bottle-holding device 8, is provided with a latch hook 11, adapted to pass through a slot 12, in the middle box portion 2, wherein said latch hook 11, hooks on to a pivoted member 13, in the form of a bell crank, the lower end 14, of which is formed to project through a slot 4^a, in the side of the coin chute 4, as indicated in Fig. 4, said member 13, being normally held in the position indicated in Fig. 4, by means of a spring 15. The end of the member 13, operates to stop and support the coin, in the manner indicated by the broken circular line in Fig. 4, until said coin is pushed down, in a manner hereinafter described, so as to rock said member 14, sufficiently to release the upper hooked end

thereof, which is in holding engagement with the latch hook 11, on the bottle support 8. Thus is a full bottle of milk inserted, supported and locked in the device.

5 An empty bottle supporting device 16, is hingedly mounted, as at 17, to the opposite side of the middle box portion 2, as indicated in Figs. 1 and 3, said empty bottle supporting device comprising a box-like member open at two sides, and its top as indicated, and having in its upper portion a U-shaped supporting member, or shelf 18, adapted to support an empty bottle 19, as indicated in Figs. 1 and 3. The supporting 10 U-shaped plate at its inner side end is provided with a locking aperture 18^a, adapted when said supporting device 16 is closed, to be engaged by a hook member, or lever, 20, the form of which is indicated in broken 15 lines in Fig. 1, said hook member being pivotally mounted, as at 21, and provided with a projecting lug portion 22, and at its lower end with a toe-portion 23, as will be seen in Figs. 1 and 5. The toe-portion 23, projects 20 into slot 5^a of coin chute 5, as indicated in Fig. 4. The member 20 is held in normal engagement position, as shown in Fig. 1, by the upper end of spring 44, also attached to lever 41. A long lever 24, is pivotally 25 mounted, as at 25, within the box portion 1, of the structure, said lever extending lengthwise of said box, as indicated in Fig. 3, and shown in section in Fig. 5, and it has an L-shaped portion 24^a, formed on its outer end 30 which projects into a position in which it is engaged by the body of the empty bottle 19, inserted in the device 16, whereupon as 35 said device 16 is closed, said lever 24, is pushed rearwardly to the position indicated 40 in broken lines, Fig. 3, by the body of the bottle 19, and is here held by reason of the engagement of the empty bottle with said L-shaped portion 24^a, of said lever 24. A 45 wedge-shaped cam member 26, is mounted on said lever 24, as shown in Figs. 3 and 5, and just the end of which is seen in Fig. 1, operating upon the lug 22, of the member 20. Also secured to a rounded portion 24^b, of said lever 24, is a lever 27, which projects 50 along the inside wall of the box member 2, being held in place by means of a clip 28, said lever 27 being of angle form at its free end with an upwardly projecting point 27^a, at the clip 28, and a downwardly extending 55 L-portion 27^b, resting upon an arch spring 29, supported at its opposite ends upon two bracket members 30—30, as indicated in Fig. 4, which tends to move the free end of said lever 27, upwardly, so that the point 27^a, thereon, hooks on to the clip 28, and thus 60 prevents the lever 24 from being pushed backwardly. The end of said lever 27, also prevents the bell crank lever 13, from being moved to the right at its lower end, so long 65 as the lever 27 is in the position shown in

Fig. 4. Said lever 27, however, also has a downwardly projecting hooked portion, as 70 27^c, projecting into a slot 5^a, in the coin chute 5, as indicated in Fig. 4, in position to stop a coin which may be inserted in the 75 coin chute 5, as will be clear from Fig. 4, in which the coin is indicated in broken circular lines.

Secured to the L-portion 27^b, of said lever 27, is an upwardly projecting portion 27^d, shown in section in Fig. 4, and shown in side view in Fig. 5. Secured to the bottle holding device 16, near its hinge 17, is a cam plate 31, shown in top plan view in Fig. 3, and seen in edge view in Fig. 5, said 80 cam plate 31, having a downwardly projecting portion with a curved cam surface 31^a. A lever 32, pivotally mounted, as at 33, has one end extended under the cam plate 31, as indicated in Fig. 5, and its other end extended in the opposite direction and provided with a downwardly projecting L-portion 32^a, provided with a notch 32^b, adapted to hook down over the long lever 24, as shown in section, Fig. 5, when said lever 90 32, is allowed to drop by the cam plate 31, which operates on its short end. The upwardly projecting portion 27^d, of lever 27, engages the under side of the pivoted lever 32, in the manner shown in Fig. 5, and while 95 said lever 32 is in its down position, it holds the lever 27, down sufficiently to allow the upwardly projecting point 27^a, on the lever 27, to pass under the clip 28. The free end of the lever 27, is thus held down during the 100 first part of the closing movement of the empty bottle holding device 16, by said lever 32, and until the short end of the lever 32, is reached by the curved cam portion 31^a, of the cam plate 31, so that the initial 105 movement of the lever 24, backwardly, caused by the engagement therewith of the empty bottle, moves said lever 27, outwardly sufficiently to start its point 27^a, under the clip 28. This is accomplished just before 110 the lever 32, is rocked into the position shown in Fig. 5, in order to fully release the lever 24, and permit its full backward movement by the bottle. A spring 34, is attached to the wall of the middle box 2, and extended 115 to and connected with the long lever 24, as indicated in Figs. 3 and 5, so as to normally hold said long lever 24, drawn inwardly, as shown in full lines, Fig. 3. Also mounted through the middle box portion 2, 120 is a shaft 35, having mounted thereupon two operating fingers 36—37, and having mounted upon its outer end an operating lever 38, said fingers 36 and 37 being positioned when 125 rocked downwardly by the turning of said crank 38, to engage the coins in the coin chutes 4 and 5, for the purpose of pressing said coins downwardly in a manner to rock the lever 27, and the toe 23 of member 20, and also the lever 14, of the bell crank 13, 130

downwardly. Said fingers 36 and 37, are normally and yieldingly held in upright position by means of a spring 36^a. The back wall 1^a of the structure is intended to be 5 screwed to the support for the device, by means of the screws 39—39. The box portion 1, therefore, is preferably constructed to be opened away from said back wall, and to this end is hinged on the same pin 25, 10 that the lever 24, is hinged upon, which pin 25 extends through said box from top to bottom, as indicated in Fig. 4. As a means for locking the box 1, to said back wall 1^a, said wall is provided with a bracket 40, and 15 said box is provided with a lever 41, hinged, as at 42, and having a hook 43, adapted to hook to said bracket 40. Said locking lever is held in locked position by means of a spring 44, Fig. 5. The front edge of the 20 middle box portion 2, is provided with a door member 2^a, adapted to be opened outwardly as indicated in broken lines, Fig. 4, for the purpose of affording access to the interior of said middle box portion, for the 25 purpose of removing the coins discharged from the lower ends of the coin chutes, said door 2^a, being provided with an aperture 2^b, adapted to pass over a locking plate 2^c, constructed to receive a padlock, or other locking 30 means, in a manner which will be clearly understood from Figs. 1 and 4.

The operation of the device may be briefly described as follows: Assuming that the device is open, as indicated in Fig. 3, the milk 35 man inserts a full bottle of milk in the left hand compartment, and closes the holding device 8, whereby the bottle is supported by its neck, as indicated in Fig. 1, the hook 11, on said device 8, passing through the opening 12 in the casing, and hooking into holding engagement to the hook of the bell crank 13, within said casing, whereby said holding device 8 is locked with the full bottle of milk supported therein. A coin in payment 40 for the milk is placed in the coin chute 4, and is stopped in the position indicated by the broken circular lines, Fig. 4, and even though the crank 38 be turned in an endeavor to force the coin downwardly, by 45 means of the finger 37, on the shaft 35, this can not be accomplished for the reason that the end of the lever 27, prevents the bell crank lever 13, from being rocked sufficiently to release its hook 13, from the hook 11, on 50 the holding device 8. If a coin be also placed in the coin chute 5, to pay for the bottle in which the milk is contained, and then the crank 38 be turned, the coin in the coin chute 5 will first be pressed downwardly sufficiently to press the lever 27, downwardly 55 against the tension of the spring 29, until its point 27^a, will pass under the clip 28, whereupon the continued movement of the crank 38, will press the coin in the coin chute 4, downwardly, thus rocking the bell 60 crank 13, and at the same time pushing the lever 27 outwardly, with the long lever 24, sufficiently to clear the hook 11, on the holding device 8, and permit it to be opened, and the full bottle to be removed. If, instead of placing a coin in the coin chute 5, to pay for the bottle, the customer places a coin in the coin chute 4, to pay for the milk, and places an empty bottle in the holding device 16, then the operation of closing the device 70 75 16 with the empty bottle therein will release the full bottle. This is accomplished in the following manner: The empty bottle engages the end 24^a of the lever 24, forcing it backwardly to the broken line position, Fig. 3. 80 In doing this, the cam plate 31, has rocked the lever 32, Fig. 5, so that its rear end 32^a, is lifted to the position shown in full lines, so as to permit said lever 24, to be forced backwardly by the bottle as the device 16 is 85 closed. The cam block 26, on said lever, is also moved back away from the lug 22, on the lever 20, the upper end of which drops into the aperture 18^a, in the U-shaped supporting plate 18, which supports the bottle, 90 thereby locking device 16. The lever 24, moving backwardly, moves the end of lever 27, away from the lower portion 14, of the bell crank 13, so that a coin in chute 4, being forced downwardly by the finger 37, on 95 operating lever 38, rocks crank 13, and releases latch hook 11, permitting the removal of the full bottle in the left hand compartment.

In case an empty bottle is not used in device 16, and it is closed, the lever 24 is not forced backwardly, and by the upward movement of lever 32, caused by cam 31^a, and the member 27^a, caused by spring 29, the point 27^a, on lever 27, is raised and 100 locks behind clip 28. The crank arm 13, cannot then be moved by the coin in coin chute 4, until a coin has also been placed in coin chute 5, to operate lever 27, in the manner previously described. The milk man, 105 to remove the empty bottle in device 16, which is locked by catch 20, must drop a slug in coin chute 5, and operate handle 38, the finger 36, forcing the slug downward and operating lever 27, and also pressing toe 110 member 23, of catch 20, downwardly, which raises catch 20, and releases device 16, allowing the empty bottle to be removed. As long as device 16 contains no bottle, it remains open, by reason of cam 26, attached to 115 lever 24, engaging lug 22, on catch 20, by means of spring 34, attached to lever 24. As long as closure 16 remains open, lever 24 is prevented from being moved backwardly by reason of notch 32^b, of lever 32, locking 120 125 device 16, behind said lever 24.

I am aware that many changes in my device as here shown and described can be made without departing from the spirit thereof, and I do not, therefore, limit my in- 130

vention except as I may be limited by the hereto appended claims.

I claim:

1. A locking device of the character referred to, comprising in combination, a structure adapted to receive and hold two bottles, inter-dependent locking mechanisms for locking said bottles in said structure, coin-controlled means for unlocking said locking mechanisms, and means for operating the same, substantially as described.

2. A locking device of the character referred to, comprising in combination, a structure adapted to receive and hold two bottles; inter-dependent, coin-controlled locking mechanisms for locking said bottles in said structure, a coin chute for each of said locking mechanisms, and operating means common to both of said coin chutes and adapted to operate on the coins placed therein, for releasing one of said locking mechanisms.

3. A locking device of the character referred to, comprising in combination, a structure provided with two bottle-holding devices, a coin-controlled locking mechanism for locking one of said bottle-holding devices, and means controlled by the other bottle-holding device and coöperating with said locking mechanism, whereby the closure of said latter bottle-holding device with a bottle therein, and a coin for said coin-controlled locking mechanism are required to release the locked bottle-holding device.

35 4. A locking device of the character referred to, comprising in combination, a structure having two bottle-holding devices, coin-controlled locking mechanisms for locking one of said bottle holding devices, two coin chutes for said locking mechanisms, and operating mechanism common to both of said coin chutes and adapted to operate on coins placed in said coin chutes to release the locked bottle-holding device.

45 5. A locking device of the character referred to, comprising in combination, a structure having two bottle holding devices, a coin-controlled locking mechanism for locking one of said bottle holding devices, a coin chute for receiving the coin, coöperating mechanism operable by a bottle in the other bottle-holding device as it is closed, whereby a bottle in said latter bottle-holding device, and a coin in said coin chute is necessary to release the locked bottle-holding device, substantially as described.

60 6. In a bottle locking device of the character referred to, in combination, a structure having two bottle-holding devices with means for locking the same in closed positions, a coin-controlled mechanism for one of said devices, and coöperating bottle-controlled mechanism operable by a bottle placed in the other of said bottle-holding devices, whereby a coin and an empty bottle

are required to release the locking mechanism of the other bottle-holding device.

7. In a bottle locking device of the character shown and described, a structure having two bottle-holding devices, locking mechanisms for said devices, coin-controlled mechanisms with coin chutes for releasing the locking mechanisms of said bottle-holding devices, a mechanism adapted to be operated by a bottle placed in one of said bottle-holding devices, and operating connections between said coin-controlled and said bottle-operated mechanisms, whereby a coin in one of said coin chutes and a bottle in one of said holding devices, or a coin in each of said coin chutes, is required to release the locking mechanism of the other bottle-holding device.

8. A locking device of the character shown and described, having two bottle-holding devices with locking mechanisms therefor, one of said devices being adapted to receive a full bottle and the other of said devices being adapted to receive an empty bottle, and means for unlocking the locking mechanism of the bottle holding device, adapted to receive the full bottle, said means comprising coin-controlled mechanism with inter-connections operable by a bottle in the bottle-holding device adapted to receive the empty bottle, whereby a coin and an empty bottle are required to release the locking mechanism of the bottle holding device for the full bottle.

9. A locking device of the character shown and described, comprising a structure having two bottle holding devices, locking mechanisms for said devices, one of said devices being adapted to receive a full bottle and the other an empty bottle, means controlling the locking mechanism for the device adapted to receive the full bottle, comprising a coin chute, a releasing member operable by a coin in said coin chute, means for pressing said coin downwardly to operate said releasing member, and means operable by a bottle placed in said empty bottle-holding device controlling the movement of said releasing member, whereby an empty bottle and a coin are required to release the locking mechanism for the full bottle-holding device.

10. A locking device of the character shown and described, having two bottle-holding devices with locking mechanisms therefor, one of said devices being adapted to receive a full bottle and the other of said devices being adapted to receive an empty bottle, and means for unlocking the locking mechanism of the bottle holding device adapted to receive the full bottle, said means comprising coin-controlled mechanism with inter-connections operable by a bottle in the bottle-holding device adapted to receive the empty bottle, whereby a coin and an empty

bottle are required to release the locking mechanism of the bottle holding device for the full bottle, and a coin-controlled releasing mechanism for unlocking the bottle-
5 holding device for the empty bottle, substantially as described.

Signed at Portland, Multnomah county, Oregon, this 14 day of January, 1916.
